DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

A schedule table in a programming system for controlling the selection of a task and the execution of the task is provided. The table comprises a plurality of fields. Each of the fields is provided with parameters to enable the above-mentioned control. These parameters are chosen to implement the principles of "working set size" and "balanced core time." A first set of parameters, termed the "Starting Set," are employed to handle new inputs from the terminal. The Starting Set functions to control responsiveness by yielding control to new inputs, controlling task growth in real memory by folding, and sorting long running tasks by working set size. A second set of parameters, termed the "Looping Set," controls system efficiency and throughput by using balanced core time to favor efficient programs, estimating the working set time at each time slice, and delaying long running tasks to improve responsiveness. Third, fourth, and fifth sets of parameters termed the "Await," "Holding," and "Waiting-for-Interlock" sets control special programs and special conditions such as interlock handling for all programs.
